ELECTRIC PLUG RECEPTACLE

Harry Zucker, New York, N. Y.

Application March 1, 1932. Serial No. 596,091

1 Claim. (Cl. 247—3)

This invention relates to receptacles for electric attachment plugs and comprehends a receptacle to take the place of the usual wall or baseboard outlets.

5 The general practice of providing one or more permanently located wall or baseboard outlets in a room, whether in an office, store, apartment or private dwelling, has not proven highly satisfactory, due to the fact that changes 10 in the arrangement of the furniture or other room fixtures frequently requires a re-location of the outlets.

It is, therefore, the object of the present invention to provide an improved continuous outlet or 15 receptacle which preferably extends completely across the walls of a room adjacent to and ostensibly forming a part of the baseboard, to afford means for operatively receiving one or more attachment plugs at any desired location and 20 suitable to any arrangement of the furniture or other fixtures in the room.

The invention further comprehends a receptacle or outlet of the character set forth which is not unduly complicated in its construction and 25 which may therefore be economically produced and installed, and one which is safe, convenient, efficient and which does not detract from the general appearance of the finish of the room.

With the above recited and other objects in 30 view, reference is had to the following description and accompanying drawing, in which there is exhibited one example or embodiment of the invention, while the claim defines the actual scope of the same.

35 In the drawing:

Figure 1 is a sectional perspective view of an outlet or plug receptacle constructed in accordance with the invention and illustrating an attachment plug associated therewith.

40 Figure 2 is a fragmentary enlarged vertical sectional view.

Fig. 3 is a fragmentary sectional perspective view of one of the outer contact supporting sections of the receptacle body.

45 Referring to the drawing by characters of reference, A designates generally the receptacle body, which is constructed of a suitable insulating material and which is preferably of rectangular cross sectional configuration and of a thickness 50 to coincide with the usual baseboard B of a room, upon the upper edge of which baseboard the body A is mounted. If desired, a moulding strip C may be arranged over the upper edge of the body A to constitute a finish for the structure. The body A is so fashioned or constructed

as to provide parallel longitudinally extending grooves D and E which are spaced apart to receive therein the contact fingers F and G of a standard attachment plug H at the extremity of an extension cord J. Continuous resilient contact strips K and L are located within the body A and respectively extend at an angle from one wall of each groove D and E and intersect the groove for frictionally engaging with and transmitting electrical energy to the fingers of plugs 65 inserted in the grooves at any point throughout the length of the body A, it being understood that the house current is supplied in any desired manner to the contact strips K and L. In the present instance, the body A is disclosed as made 70 up of three sections or strips, namely, an intermediate section 5 and upper and lower or outer sections 6 and 7, the latter two being of identical construction. The intermediate section 5 is of a depth or vertical thickness approximating the 75 spacing between the fingers F and G of a standard attachment plug H illustrated. The latter sections 6 and 7 have the inner faces 8 which confront the intermediate section rabbeted as at 9 so that when the three sections are assembled 80 as illustrated in Figures 1 and 2, the rabbeted portions 9 define, together with the intermediate section 5, the contact finger receiving grooves F and G. The rabbeted portions are further provided with grooves 10, and within each groove 85 the contact strips K or L are secured with a portion protruding into the remainder of the rabbeted portion 9 to be disposed in intersecting relation to the contact finger receiving groove for frictionally engaging and transmitting electrical energy to the plug fingers. As disclosed, 90 the several sections 5, 6 and 7 are formed with aligned apertures 11, 12 and 13 at longitudinally spaced points to receive therethrough the assembling rivets 14. Obviously, the body A may be 95 secured in position in any desired manner, but as illustrated in the present instance, apertured attaching feet or lugs 15 are provided to receive therethrough screws or other fastening devices for anchorage in the wall joists.

100 It is intended in practice to provide each wall of the room with a continuous extending outlet or receptacle body A so that an outlet for the current may be provided at any point in the room desired, thereby avoiding the necessity of 105 long extension and the unsightly appearance of a plurality of isolated wall or baseboard sockets or outlets.

What is claimed is:

110 A continuous receptacle for electric attachment

plugs including an elongated body of insulating material having parallel grooves for receiving the plug terminal fingers and continuous resilient contact strips arranged in said body and normally intersecting the grooves for frictionally engaging with and transmitting electrical energy through said fingers, said body being fabricated of upper, lower and intermediate sections, the latter being throughout of a depth approximating the spacing of the standard plug fingers and

the former sections having the faces confronting the intermediate section rabbeted to define the finger receiving grooves, the rabbeted faces which confront the intermediate section having grooves provided with rearwardly angled walls and the contact strips being secured against said angled walls and protruding at a rearward inclination into the finger receiving grooves.
